UNITED STATES PATENT OFFICE.

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA.

INTERLEAVING APPARATUS.

Application filed June 13, 1927. Serial No. 198,548.

The present invention relates to apparatus for piling sheets, and interposing at intervals between a series of sheets, a sheet of a different character. For example in the manufacture of tablets, sheets of paper may be ruled and deposited in a lay-boy or other piling mechanism, and at intervals backing sheets of card-board can be deposited in the lay-boy, thus creating a pile that may be afterwards formed into completed tablets. It will be understood that it is not limited to the above specific example, but may be employed in various ways well known to those skilled in the art.

In the accompanying drawings:

Figure 1^a is a side elevation of one portion of the apparatus.

Figure 1^b is the corresponding side elevation of the other portions, Figure 1^b being a continuation of Figure 1^a.

Figure 2 is a longitudinal sectional view through the structure shown in Figure 1^a.

Figure 3 is a side elevation on an enlarged scale of the second or interleaving feeder,

Figure 4 is a view in elevation of the opposite side of the interleaving feeder.

Figure 5 is a longitudinal sectional view through the interleaving feeder,

Figure 6 is a top plan view of said interleaving feeder and the associated lay-boy,

Figure 7 is a view in elevation of the mechanism for controlling the operation of the suction roller of the interleaving feeder,

Figure 8 is a detail sectional view on the line 8-8 of Figure 7,

Figure 9 is a view in elevation of the table-elevating mechanism of the interleaving feeder,

Figure 10 is a sectional view on the line 10-10 of Figure 9,

Figure 11 is a sectional view on the line 11-11 of Figure 5,

Figure 12 is a cross sectional view of the table of the interleaving feeder and its supporting means.

In the embodiment illustrated, two frames 13 and 14 are employed. In advance of the frame 13 is located a feeding mechanism, designated generally by the reference numeral 15. This mechanism may be of any well-known type, an example of which is that disclosed in my co-pending application, Serial No. 198,549, filed June 13, 1927.

In the embodiment disclosed, the feeder is shown as taking the paper from a roll 16 and passing it around rollers 16^a and thence through a cutter consisting of coacting rollers 17 and 18. The roller 17 has a knife blade 19 cooperating with a ledger bar 20 carried by the roller 18.

In the rear end of the frame 14 is a lay-boy 21 that may be of any well-known or desired character. Preferably, however, its construction corresponds to that disclosed in my prior Patent, No. 1,560,015, dated November 3, 1925.

Mounted on the rear end of the frame 13 is a ruling mechanism, preferably in the form of disc ruling devices, shown at 22. Lower and upper coacting conveyor tapes 23 and 24 carry the sheets from the feeder 15 to the ruling mechanism. Behind the ruling instrumentalities is a conveyor, comprising a front member 25 and a rear member 26. The front member consists of a lower endless cloth or tapes 27 and upper coacting cords or tapes 28. The rear member 26 comprises cooperating lower and upper tapes 29 and 30. The member 26, as will be evident, delivers the sheets into the lay-boy 21.

Interposed between the conveyor members 25 and 26, and as shown more particularly in Figure 5, are convergently disposed guideways 31 and 32. These guideways are formed by a series of upper plates 33 carried by a cross rod 34, a lower series of plates 35 carried by a cross rod 36, and a series of intermediate triangular plates 37 mounted on the cross rod 38. The upper downwardly inclined guideway 31 directs the sheets from the first conveyor member 25 to the second conveyor member 26, and said second conveyor member delivers the sheets into the lay-boy 21.

At the front end of the rear frame 14 is located an interleaving feeder, designated generally by the reference numeral 39. This is a pile feeder, comprising a pile-supporting table 40, having sleeves 41 slidably mounted on standards 42 (see Fig. 12). In the embodiment shown this table is hung on sprocket chains 43 that pass over sprocket wheels 44 journaled on the upper ends of the standards. Suitable mechanism is employed for automatically elevating the table 100 as the sheets are moved from the top of

the pile. While this mechanism may be of any desirable character, preferably the following is provided. The sprocket wheels 44 are carried on shafts 45 which also carry 5 worm gears 46. A cross shaft 47 is provided, having worms 48 that mesh with the worm gears 46 (see Fig. 10). On this cross shaft 47 is fixed a ratchet wheel 49 (see Figs. 9 and 10). Loosely journaled on the shaft 47 10 alongside the ratchet wheel 49 is a swinging pawl carrier 50, on the upper end of which is pivotally mounted a pawl 51 that operates on the ratchet wheel 49. This pawl carrier has a depending portion provided with a 15 pin 52 that is engaged in the slot 53 of a link 54. This link has mounted at its other end a crank pin 55 carried by a constantly rotating crank disc 56. The pawl carrier also has an outstanding stop finger 57, and 20 a detent arm 58 pivoted at 59 is adapted to swing into and out of a position beneath the stop finger 57. This arm 58 is connected by a link 60 with an arm 60^a carried by a rock shaft 61, and said rock shaft has se- 25 cured to it a forwardly extending arm 62 provided with a depending finger 63 adapted to rest on the pile of sheets. As will be clear from Figure 3, when the pile of sheets on the table 40 is sufficiently high, the arm 30 62 will be elevated, thereby swinging the detent arm 58 to a position beneath the stop finger 57. The pawl carrier 50 therefore will have no active movement and the link 54 will slide freely on the pin 52. 35 As the sheets are removed from the top of the pile the arm 62 will move downwardly until the arm 58 is moved out of the path of the stop finger 57. The pawl carrier will then swing rearwardly, so that the pawl 51 40 will ride over one or more teeth of the ratchet wheel 49, and as the link 54 moves rearwardly, the pawl carrier will be swung in the opposite direction, thereby causing the ratchet wheel 49 to be turned. This ef- 45 fects the corresponding movement of the cross shaft 47, thereby rotating the shafts 45 and causing the elevation of the table until the detent 58 is again swung to a position beneath the stop finger 57. 50 The means for feeding the sheets from the interleaving feeder is preferably a suction roller. It is shown at 64 in Figures 5 and 6 and may be of any desired character, though preferably either like that 55 shown in my Patent No. 1,494,303, May 13, 1925, or of the character disclosed in my copending application, Serial No. 149,471. Connected to this suction roller 64 is a suction conduit 65, which as will be clear by 60 reference to Figures 1^a and 1^b leads to the intake side of a suitable fan 66. The outlet side of said fan is connected by a hose line 67 to blast nozzles, indicated at 68, which as is well known, serve to deliver blasts of 65 air against the upper edge of the pile of

sheets to separate the same. In the conduit 65 at the first feeder is a controlling valve 69, shown particularly in Figures 1 and 7. This valve is preferably of the type disclosed in my former Patent, No. 1,408,688, 70 dated March 7, 1922, and consists of a casing 70, through which the air passageway 71 passes. In this casing is a reciprocatory valve member 72 having a suitable port 73 that is movable into and out of alinement 75 with the passageway 71 to permit or stop the flow of air therethrough. The valve member 72 in this structure is connected by a link 73^a with one arm 74 of a bell crank element pivotally mounted, as shown at 75, and 80 having its other arm 76 arranged in depending relation and limited in its movement in one direction by a stop 77. A ratchet wheel 78, journaled on the first feeder 15, is provided with a sprocket wheel 79, 85 around which passes a sprocket chain 80 that operates around a lower idler sprocket wheel 81. On this sprocket chain are mounted one or more lugs 82 that are adapted to engage the arm 76 and swing the same, there- 90 by swinging the crank arm and moving the valve. The ratchet wheel 78 is engaged by a pawl 83 carried by an arm 84, and this arm has a link connection 85 with an eccentric strap 86, and surrounding an ec- 95 centric 87, preferably mounted on one of the cutter rolls of the first machine.

It will be evident by reference to Figure 7 that upon the cutting and delivery of each sheet by the first feeder, the sprocket wheel 78 will have one increment of movement and the sprocket chain will be given a corresponding movement. Therefore at intervals a lug 82 will engage the arm 76, and consequently the valve will be elevated 100 to open the conduit 65 to the suction side 105 of the pump 66. When this occurs the suction roller of the interleaving feeder will be made active so that a sheet will be fed thereby.

It is believed that the operation of the apparatus can now be made clear. Sheets are successively and continuously fed from the first feeder and successively passed through the ruling mechanism 22 and are 110 delivered by the tangent conveyer members 26 and the interposed guideway 31 to the lay-boy 21. At predetermined intervals the suction roller of the interleaving feeder will be actuated as above described, whereupon 115 the sheet will be fed therefrom and will be directed by the lower guideway 32 to the second conveyor member 26 so as to be delivered thereby into the lay-boy. It is relatively immaterial whether the sheets from 120 the first feeder and the second feeder meet and overlap at the entrance end of the conveyor 34 for said conveyor will carry all to the lay-boy 21. The consequence is that a certain number of ruled sheets will first be 125 130

delivered, then a sheet, as for example a backing sheet of a tablet will be placed on the pile, after which another series of ruled sheets will be delivered and so on until a 5 stack or pile has been produced. Obviously the number of sheets can be varied and different combinations readily obtained.

From the foregoing, it is thought that the 10 construction, operation and many advantages of the herein described invention will be apparent to those skilled in the art, without further description, and it will be understood that various changes in the size, shape, proportion and minor details of construction 15 may be restored to without departing from the spirit or sacrificing any of the advantages of the invention.

What I claim, is:

1. In apparatus for interleaving sheets, 20 the combination with means for conveying sheets in successive order and in an edge-wise direction, and mechanism for introducing other sheets periodically and in an edgewise direction between a plurality of 25 the sheets thus conveyed.

2. In apparatus for interleaving sheets, the combination with means for conveying sheets in successive order and in an edge- 30 wise direction, and mechanism beneath the path of said sheets for introducing other sheets periodically and in an edgewise direction between a plurality of the sheets thus conveyed.

3. In apparatus for interleaving sheets, 35 the combination with a conveyor for carrying sheets one after another in an edgewise direction, of means for feeding sheets successively thereto, and mechanism beneath said conveyor and the sheets carried thereby 40 for periodically delivering other sheets periodically and in an edgewise direction between a predetermined number of sheets carried by the conveyor.

4. In apparatus for interleaving sheets, 45 the combination with a sheet conveyor, of means for feeding sheets successively thereto, a sheet holding means beneath the path of the sheets, and means for periodically removing a predetermined number of sheets 50 from the sheet holding means and interposing them between sheets carried by the conveyor.

5. In apparatus for interleaving sheets, 55 the combination with a sheet conveyor, of means for feeding sheets successively thereto, a sheet holding means beneath the path of the sheets, a suction device for removing sheets from the sheet holding means and interposing them between sheets carried by 60 the conveyor, and means for periodically operating the suction device.

6. In apparatus for interleaving sheets, 65 the combination with a sheet conveyor, of means for feeding sheets successively there- to, a sheet holding means beneath the path

of the sheets, a suction roller for removing sheets from the sheet holding means and interposing them between sheets carried by the conveyor, means for creating suction in said roller, a valve controlling said suction, 70 and means for operating the valve in predetermined timed relation to the sheets moved by the conveyor.

7. In apparatus for interleaving sheets, 75 the combination with a sheet piling mechanism, of means for delivering sheets successively to the piling mechanism, and mechanism located below the sheet delivering means for periodically delivering sheets to a position to be interposed between a pre- 80 determined number of the sheets delivered to the piling mechanism by said means.

8. In apparatus for interleaving sheets, 85 the combination with a lay boy, of means for conveying sheets successively to the lay boy, and means in advance of the lay boy and beneath the conveying means for periodically delivering sheets to be deposited in the lay boy between the sheets conveyed thereto by the conveying means.

9. In apparatus for interleaving sheets, 90 the combination with a lay boy, of sheet conveying mechanism that delivers thereto, means for feeding sheets successively to the conveyor, means for supporting a pile 95 of sheets between the feeding means and lay boy, and means for periodically delivering sheets carried by the supporting means to the conveying mechanism to be delivered thereby to the lay boy between the sheets 100 delivered by the conveying mechanism from the feeding means.

10. In apparatus for interleaving sheets, 105 the combination with a lay boy, of sheet conveying mechanism that delivers thereto, means for feeding sheets successively to the conveyor, a vertically movable sheet supporting table beneath the conveying means and between the feeding means and the lay boy, means for periodically delivering sheets 110 carried by the table to the conveying mechanism to be delivered thereby to the lay boy between the sheets delivered by the conveying mechanism from the feeding means, and means for automatically elevating the table 115 as the sheets are delivered therefrom.

11. In apparatus for interleaving sheets, 120 the combination with a lay boy, of sheet conveying mechanism that delivers thereto, means for feeding sheets successively to the conveyor, a vertically movable sheet supporting table beneath the conveying means and between the feeding means and the lay boy, a rotary suction roller for periodically delivering sheets carried by the table to the 125 conveying mechanism to be delivered thereby to the lay boy between the sheets delivered by the conveying mechanism from the feeding means, means for automatically elevating the table as the sheets are delivered there- 130

from, and means controlled by the first feeding means for periodically creating suction in the suction roller.

12. In apparatus for interleaving sheets, the combination with a sheet piling mechanism, of a sheet feeder, a conveyor for delivering sheets from the feeder to the piling mechanism, a second sheet feeder between the first feeder and the sheet piling mechanism and including a suction roller that delivers sheets to the sheet piling mechanism, and means controlled from the first feeder for causing the suction roller to periodically operate.
13. In apparatus for interleaving sheets, the combination with a sheet piling mechanism, of a sheet feeder, a conveyor for delivering sheets from the feeder to the piling mechanism, a second sheet feeder between the first feeder and the sheet piling mechanism and including a suction roller that delivers sheets to the sheet piling mechanism, and means controlled from the first feeder for causing the suction roller to periodically operate, said controlled means being variable to change the period of operation of the suction roller.

14. In apparatus for interleaving sheets, the combination with a sheet piling mechanism, of a sheet feeder, a conveyor for delivering sheets from the feeder to the piling mechanism, and comprising members arranged end to end, and a second sheet feeder beneath the conveyor and having means for delivering sheets between the conveyor members and to the second member.

15. In apparatus for interleaving sheets, the combination with a sheet piling mechanism, of a sheet feeder, a conveyor for delivering sheets from the feeder to the piling mechanism and comprising members arranged end to end and a guideway for directing sheets from the first to the second conveyor member, a second sheet feeder beneath the conveyor and having means for delivering sheets between the conveyor mem-

bers, and a guideway between the members for directing the sheets from the second feeder to the second conveyor member.

16. In apparatus for interleaving sheets, the combination with a sheet piling mechanism, of a sheet feeder, a conveyor for delivering sheets from the feeder to the piling mechanism and comprising members arranged end to end, convergent guides between the members, one of said guides directing sheets from the first to the second member, and sheet feeding means delivering sheets to the other guide to be thereby directed to the second member.

17. In apparatus for interleaving sheets, the combination with a lay-boy, of a sheet feeding mechanism, a conveyor for carrying sheets from the feeding mechanism to the lay-boy and comprising spaced conveying members, guides between the members, one of said guides directing sheets from the first to the second member, a sheet feeding means including a suction roller that delivers sheets to the other guide and said latter guide directing the sheets to the second member, and means for periodically causing the suction roller to become active.

18. In apparatus for interleaving sheets, the combination with a lay-boy, of a sheet feeding mechanism, a conveyor for carrying sheets from the feeding mechanism to the layboy, and comprising spaced conveying members, guides between the members, one of said guides directing sheets from the first to the second member, a sheet feeding means including a suction roller that delivers sheets to the other guide and said latter guide directing the sheets to the second member, a suction conduit connected to the roller, a valve in said conduit, and means operating with the first feeder for periodically operating the valve to permit suction through the conduit and roller.

In testimony whereof, I affix my signature.

ALBERT BROADMEYER.
